UNITED STATES PATENT OFFICE.

WILLIAM A. GEIGER, OF CHICAGO, ILLINOIS, ASSIGNOR TO WILLIAM H. MINER, OF CHAZY, NEW YORK.

ROLLER SIDE BEARING FOR RAILWAY-CARS.

1,223,323.

Specification of Letters Patent. Patented Apr. 17, 1917.

Application filed October 22, 1914. Serial No. 867,990.

To all whom it may concern:

Be it known that I, WILLIAM A. GEIGER, a citizen of the United States, residing at Chicago, in the county of Cook and State 5 of Illinois, have invented a certain new and useful Improvement in Roller Side Bearings for Railway-Cars, of which the following is a full, clear, concise, and exact description, reference being had to the accompanying drawings, forming a part of 10 this specification.

This invention relates to improvements in roller side bearing for railway cars.

The object of the invention is to provide 15 a side bearing for railway cars which consists of few parts that may be cheaply and easily manufactured and assembled and which will provide a bearing efficient in operation.

20 The invention furthermore consists in the improvements in the parts and devices and in the novel combinations of the parts and devices as herein shown, described or claimed. And although I herein show and 25 describe in detail one form of my improvements, yet I do not wish to be confined to the details shown and described, inasmuch as I am aware that various changes and 30 modifications may be made in the arrangement and details of the parts without departing from the spirit of the invention, and I contemplate all such changes and 35 modifications as fall within the scope of the claims forming a part hereof.

35 In the drawing, Figure 1 is an elevational view of a body and truck bolster of a railway car, showing my improvements in connection therewith. Fig. 2 is an enlarged vertical sectional view taken substantially 40 on the line 2—2 of Fig. 1, and showing more particularly the improved side bearing, and Fig. 3 is a similar sectional view taken substantially on the line 3—3 of Fig. 2.

45 In said drawing 10 denotes the truck bolster which is swiveled in the usual manner to the body bolster 11 and, as shown, the body bolster is provided with an integral bearing plate 12 on each side of the king pin. Coöperable with each bearing plate 50 12, is one of my improved roller bearings, designated generally by the reference A. As shown, the roller bearing A comprises a base plate or bracket B and an anti-friction roller C. The bracket B has a horizontal 55 base 14 riveted or otherwise suitably secured

to the truck bolster 10. Extending upwardly from the base 14 are two spaced arms 15—15, each of which is provided with a journal bearing 16 near the top thereof, which bearing is open at the top and 60 adapted to receive a journal 17, which journal is held in position and prevented from accidental displacement by means of strips 18 inserted through suitable slots formed in the extensions 19—19, the strip having its 65 ends bent down as indicated at 20. The journal 17, as shown, is provided at the center thereof with an enlargement 21, which is of substantially spherical formation.

70 The roller C comprises two like members 22—22, each of which is in the form of an annular disk with an opening through the center thereof, which opening consists of a flared portion 23 and a concave bearing surface 24 corresponding to the spherical 75 surface of the enlargement 21. On the inner face of each member 22—22, is provided a pair of sockets 25 and a pair of outstanding dowels or projections 26, it being obvious that the pair of dowels on one member 22 fit in the corresponding sockets of the opposite member 22 and in this way 80 prevent relative rotation of the members 22—22. To hold the members 22—22 together, a sleeve 27 is provided, which may 85 be of any suitable material, and preferably of harder metal than the members 22—22. Said sleeve 27 is provided at each edge with an inturned flange 28 which fits in corresponding grooves or recesses 29 on the outer 90 sides of the members 22.

95 From the preceding description it will be seen that the roller C is permitted not only to rotate about the journal 17, but also to oscillate thereon to thus accommodate it- 95 self to the varying angular positions of the body and truck bolsters and the sleeve 27 provides a hardened wearing surface without the necessity of making the entire roller of the same hard material, thus minimizing 100 the cost of manufacture.

I claim:—

1. A roller side bearing of the character described comprising, a bracket having a journal mounted thereon, and a roller rotatably mounted on said journal, the roller consisting of two circular members and a circumferentially extending shell inclosing and overlapping the side of said members to thereby unite the same. 105

2. A roller side bearing of the character described comprising, a bracket having a journal mounted thereon, a roller rotatably mounted on said journal, the roller consisting of two circular members and a circumferentially extending shell inclosing and overlapping the sides of said members to thereby unite the same, and coöperating means on the interior of the roller and on the journal permitting the roller to oscillate in addition to its rotative movement. 25
3. In a roller side bearing for railway cars, the combination with a supporting bracket having a journal mounted thereon, of a roller mounted on said journal, said roller comprising two circular members having interfitting dowels and sockets on their meeting faces and a sleeve for holding said members in assembled position. 30
4. In a side bearing for railway cars, the combination with a base bracket, of a journal mounted in said bracket, said journal having a spherical enlargement near the center thereof, and a roller having a trans- 35
- verse opening therethrough, said opening being enlarged near the center thereof and curved to fit said spherical enlargement of the journal, said roller comprising two members and an inclosing sleeve to hold said members together. 40
5. In a side bearing of the character described, the combination with a supporting bracket having upstanding, spaced arms, each of which is provided with a journal bearing near the top thereof and open at its upper end, of a journal mounted in said bearings, said journal having a spherical enlargement near the center thereof, and a roller rotatably and rockably mounted on said journal, said roller comprising two circular members having interfitting projections and sockets on their meeting faces and a sleeve encircling said members and flanged at its edges to bind said members together. 45

WILLIAM A. GEIGER.
